UNITED STATES PATENT OFFICE

162,164

SEWING STAND

Clarence C. Hill, Los Angeles, Calif.

Application October 21, 1949, Serial No. 5,610

Term of patent 7 years

(Cl. D3—19)

To all whom it may concern:

Be it known that I, Clarence C. Hill, a citizen of the United States, residing at Los Angeles, in the county of Los Angeles and State of California, have invented a new, original, and ornamental Design for a Sewing Stand, of which the following is a specification, reference being had to the accompanying drawings, forming part thereof.

In the drawings:

Figure 1 is a side elevational view of my design for a sewing stand;

Figure 2 is a top plan view, and

Figure 3 is a front elevational view.

I claim:

The ornamental design for a sewing stand, as shown.

CLARENCE C. HILL.
